UNITED STATES PATENT OFFICE.

DEMETRIOS P. STERGIANOPULOS, OF NEW YORK, N. Y.

PORTABLE-LAMP ATTACHMENT.

Application filed November 26, 1926. Serial No. 150,859.

This invention relates generally to portable lamp attachments, the invention having more particular reference to a novel type of portable lamp attachment embodying certain features which will add to the usefulness of the lamp. The invention has for an object the provision of an improved portable lamp attachment of novel construction and arrangement of parts.

For further comprehension of the invention, and of the objects and advantages thereof, reference will be had to the following description and accompanying drawing, and to the appended claims in which the various novel features of the invention are more particularly set forth.

Fig. 1, of the drawing, is a side elevational view of a portable lamp embodying my improved attachment.

Fig. 2, is an enlarged plan detail view of my improved attachment, partly in section, so as to expose certain interior parts.

Fig. 3, is a transverse central sectional view of a modified form of my invention.

Fig. 4, is a similar fragmentary view taken on the line 4—4 of Fig. 2.

Fig. 5, is a detail view of the lazy tong construction, showing same in an extended position.

Fig. 6, is a detail view of a cigar holder, such as may be incorporated in my improved attachment.

Fig. 7, is a detail view of a double cigar holder, designed to hold two cigars, such as may be incorporated in my improved device.

Fig. 8, is an enlarged fragmentary detail view of the locking device.

Fig. 9, is a detail view of a drinking glass and holder, such as may be incorporated in my improved device.

This invention relates generally to portable lamps, such as are usually provided with a base 10, an upright or supporting member 11, and the common shade 12, such as usually provided to shield the glare of the light, which is supported by the upright 11, and which may comprise any ordinary lighting medium such as electric light bulbs, kerosene oil, or the like, such as generally used in portable lamps of this nature. It being understood that I do not necessarily limit the use of my improved attachment to the particular type of portable lamp here described and illustrated, but to all

classes and types of portable lamps such as commonly used.

As here embodied my improved attachment comprises a base member 15, of bowl shaped, circular construction, and having an axial aperture adapted to engage over the tubular member 16, which engages over the above referred to upright 11 of the said portable lamp, and which is rigidly attached thereto. The tubular member 16 is provided with a lower flanged element 17 adapted to support the base member 15. The base member 15 is provided with apertures 18, or openings. The casing 19, is provided with an axial aperture, adapted to rotatively engage the said upright 11, and is held in place thereon, by the upper edge of the tubular member 16. The casing 19 is of circular construction, preferably curved or concave so as to add to decorative features thereto, or may be of any similar suitable shape as may be desired, and is provided with downwardly extended elements 20, adapted to enclose or cover the above referred to apertures 18 formed in the base member 15.

The base member 15 is provided with grooved elements 21, radially extended from the tubular member 16 in line with the apertures 18. The grooved elements 21 are adapted to support the lazy tong members 22, which are of ordinary construction, and which comprise the usual pivoted members, extending from, and pivotally attached to the supporting member 23, as at 24, by a pin or the like, to which is also attached one extremity of the tension spring 25, which is attached as at 26, to a pin or the like, attached to the said lazy tongs, and slidably engaged in an elongated slot formed in the upper extremity of the supporting member 23. The latter described construction is such as will permit the tension spring 25 to extend the lazy tong members 22, when the above referred to casing 19 is rotated or turned so as to open the apertures 18 provided in the base member 15. It will be understood that the above referred to lazy tong members 22 may be placed or positioned in horizontal or vertical position, as clearly shown in the accompanying drawing.

The extension member 27 is pivotally attached, as at 28, by a pin, or the like, to the base member 15, adjacent to the tubular member 17, and has attached thereto a compression spring 29 which is attached, at its

other extremity to the base member 15. The latter described construction is such as will permit the compression spring 29 to extend or move the extension member 27, as designated by the reference numeral 30, so as to further extend the said lazy tong members 22.

Referring in particular to Fig. 8 of the accompanying drawing, the lever 31, is pivotally attached, as at 32, by a pin, or the like, to the casing 19, and has attached thereto, at one extremity a button 33, and has attached at its other extremity, an extended element 34, normally held in engagement with a notch formed in the guide element 21, by a compression spring 35, positioned under the lever 31 and supported by the bracket 36 attached to the casing 19. It is understood that the button 33 is extended through an aperture formed in the casing 19. The above described construction is such as will permit the lever 31 to normally hold the casing 19 in a fixed position, so as to enclose or cover the apertures 18 formed in the base member 15.

The free extremities of the lazy tong members 22 may have attached thereto, a cigarette holder 37, adapted to hold a cigarette 38, or may have attached thereto, a cigar holder 39, or a double cigar holder 40, adapted to hold two cigars, or ash trays 41, may be attached thereto, or a holder 42, adapted to hold a drinking glass 43.

The buttons 44 are slidably positioned in the base member 15 and are provided with enlarged extremities 45, normally held in engagement with the free extremity of the lazy tong members 22, by compression springs 46. The latter described construction is such as will hold the said lazy tong members 22 in a closed position, as clearly shown in Fig. 3.

The device is normally, as shown in Fig. 3, the casing 19 being held against rotation by element 34 connected with the casing, and engaging in a notch in the guide member 21 connected with the bowl shaped member 15. The button 33 may be manually depressed to free the casing, and then the casing may be turned so that the extended elements 20 are moved from in front of the openings 18 in the bowl shaped member. Then any or all of the buttons 44 may be manually pulled downward to free the lazy tong structures 55 which are then extended thru the openings 18 by the springs 25 and 29. The various articles at the outer ends of the lazy tongs may be manually returned to normal positions by merely forcing same inwards.

Having thus described my invention, what I claim as new and desire to protect by Letters Patent of the United States is as follows:

1. In a portable lamp attachment of the class described, a tubular member adapted

to be disposed around an upright member of a portable lamp, a bowl shaped base member mounted on said tubular member and having apertures in the sides thereof, a casing rotatively mounted on said bowl shaped base member, and formed with extended elements covering the said apertures, radial guide members having grooves therein, mounted in the said base member in registration with said openings, supports slidably mounted in the grooves of said guide members, lazy tong members attached at one end to the said supports, and adapted to extend thru the openings in said base member when the casing is turned to move the extended elements from said openings, the said slidably mounted supports being adapted to move forwardly in the direction of the sides of said base member for further extending said lazy tongs thru said apertures, and means for normally urging the supports into this forwarded position.

2. In a portable lamp attachment of the class described, a tubular member adapted to be disposed around an upright member of a portable lamp, a bowl shaped base member mounted on said tubular member and having apertures in the sides thereof, a casing rotatively mounted on said bowl shaped base member, and formed with extended elements covering the said apertures, radial guide members having grooves therein, mounted in the said base member in registration with said openings, supports slidably mounted in the grooves of said guide members, lazy tong members attached at one end to the said supports, and adapted to extend thru the openings in said base member when the casing is turned to move the extended elements from said openings, the said slidably mounted supports being adapted to move forwardly in the direction of the sides of said base member for further extending said lazy tongs thru said apertures, and means for normally urging the supports into this forward position, consisting of levers pivotally mounted on said base member and engaging the said slidably mounted supports, and springs disposed between said levers and the tubular member for rotating the levers in the direction of the sides of the said base member.

3. In a portable lamp attachment of the class described a tubular member adapted to be disposed around an upright member of a portable lamp, a bowl shaped member mounted in said tubular member and having apertures in the sides thereof, a casing rotatively mounted on said bowl shaped base member, and formed with extended elements covering the said apertures, radial guide members having grooves therein, mounted in the said base member in registration with said openings, supports slidably mounted in the grooves of said members, lazy tong mem-

bers attached at one end to the said supports, and adapted to extend thru the openings in said base member when the casing is turned to move the extended elements from said 5 openings, latches mounted on the base member for normally retaining said lazy tongs in retracted positions, the said slidably mounted supports being adapted to move forwardly in the direction of the sides of 10 said base member for further extending said lazy tongs thru said apertures, and means

for normally urging the supports into this forward position, consisting of levers pivotally mounted on said base members and engaging the said slidably mounted supports, 15 and springs disposed between said levers and the tubular member for rotating the levers in the direction of the sides of the said base member.

In testimony whereof I have affixed my 20 signature.

DEMETRIOS P. STERGIANOPULOS.
